[57] CLAIM

The ornamental design for a two-compartment container, as shown and described.

DESCRIPTION

FIG. 1 is a top plan view of a two-compartment container showing my new design;

FIG. 2 is a front elevational view thereof;

FIG. 3 is a rear elevational view thereof;

FIG. 4 is a bottom plan view thereof;

FIG. 5 is a perspective view thereof; and,

FIG. 6 is a side elevational view thereof taken from the right-hand side of FIG. 1, the left-hand side view being a mirror image thereof.
